United States Patent [19]

Iino et al.

US00D361062S

[11] Patent Number: Des. 361,062

[45] Date of Patent: ** Aug. 8, 1995

[54] ELECTRONIC COMPUTER

[75] Inventors: **Masaaki Iino**, Yokohama; **Ryoichi Ishiura**, Matsudo, both of Japan

[73] Assignee: **Kabushiki Kaisha Toshiba**, Kanagawa, Japan

[**] Term: 14 Years

[21] Appl. No.: 12,978

[22] Filed: Sep. 15, 1993

[30] Foreign Application Priority Data

Mar. 17, 1993 [JP] Japan 5-7427

[52] U.S. Cl. D14/106

CLAIM

The ornamental design for an electronic computer, as shown and described.

DESCRIPTION

FIG. 1 is a top, front and right side perspective view of an electronic computer showing our new design;
FIG. 2 is a front elevational view thereof;
FIG. 3 is a left side elevational view thereof;
FIG. 4 is a right side elevational view thereof;
FIG. 5 is a rear elevational view thereof;
FIG. 6 is a top plan view thereof;
FIG. 7 is a bottom plan view thereof;
FIG. 8 is a front elevational view thereof in closed position;
FIG. 9 is a right side elevational view thereof in closed positioned; and,
FIG. 10 is a top plan view thereof in closed position.
